PRECOMBUSTION CHAMBER

Robert H. Loughran, East Hartford, Conn., assignor to United Aircraft Corporation, East Hartford, Conn., a corporation of Delaware

Application June 17, 1949, Serial No. 99,603

2 Claims. (Cl. 60—39.65)

1

This invention relates to improvements in precombustion chambers as used in burners in gas turbine power plants.

One of the problems connected with gas turbine power plant burners is the use of the proper fuel in combination with the proper fuel nozzle pressure in order that the combustion of the charge within the burner is as complete as possible. A feature of this invention is a precombustion chamber which over a wide range of fuels as well as a wide range of fuel nozzle pressures is conducive to complete combustion due to the extended transit time of the fuel particles within the combustion zone.

A problem in connection with gas turbine power plants is to provide burner operation which is insensitive to sudden changes of the rate of fuel and air flow. A feature of the invention is the localization of the critical primary combustion in and adjacent to the precombustion chamber where flows are insensitive to sudden changes of total fuel and air flow. A feature of the invention is the localization of the major portion of combustion in and adjacent to the precombustion chamber to provide fuel-air ratios conducive to complete combustion when the total fuel-air ratio is relatively low.

The invention has particular application to aircraft gas turbine power plant burners. One of the problems in aircraft gas turbines is the excessive length of the burner necessary to support combustion due to the high velocity of the gases moving through the burner. A feature of this invention is a precombustion chamber which moves the nozzle end of the burner flame upstream toward the fuel nozzle and thus enables a reduction in the overall length of the burner.

Other objects and advantages will be more particularly pointed out or will become apparent as the description proceeds.

In the accompanying drawing, in which like reference numerals are used to designate similar parts throughout, there is illustrated what is considered to be a preferred embodiment of the invention.

In the drawing:

Fig. 1 is a longitudinal sectional view of a gas turbine power plant burner unit showing the location and features of the precombustion chamber constructed according to this invention.

Fig. 2 is a sectional view of the precombustion chamber along line 2—2 of Fig. 1.

Fig. 3 is a longitudinal view of another type of precombustion chamber.

2

Fig. 4 is an end view of the precombustion chamber illustrated in Fig. 3 showing the perforated end section, as viewed from line 4—4.

Referring to the drawing in detail, the burner unit is indicated generally in Fig. 1 at 10, said burner unit having inlet 12 where combustion supporting gases enter the burner and outlet 14 from which the combustion gases are discharged. Precombustion chamber 16 where combustion commences is mounted adjacent burner inlet 12 where it is supported on legs 18 within conical shell 19. The precombustion chamber is provided with a plurality of holes 20 about its circumference and over the greater portion of its length, combustion gases exiting from the precombustion chamber through these holes. Cap 22 covers the downstream end of the precombustion chamber.

Fuel nozzle 24 is centrally located within burner inlet 12 and discharges fuel at the entrance to the precombustion chamber. Conduit 26 supplies fuel to this nozzle from a source not shown. Retractable ignitor 28 is located within burner unit 10 and adjacent to precombustion chamber 16 for starting the combustion process of the fuel-air mixture within the chamber.

Combustion supporting means entering the inlet of the burner, from a compressor or some other source upstream of the burner, divide as they pass into the burner unit. Part of the gases are directed by conical shell 30 attached to conical shell 19 to precombustion chamber 16, although a quantity is spilled out around support legs 18 into chamber 31 surrounding the precombustion chamber. The major portion of the gases entering the burner passes through annular chamber 32, of which conical shell 19 forms the inner wall, and are admitted to combustion chamber 34 through openings 36 at various stages along the length of the burner.

Gases passing over nozzle 24 pick up fuel and carry it into precombustion chamber 16 where the mixture is burned. The combustion which takes place within this chamber causes an increase in the specific volume of the gases with the result that the flow of flame from the precombustion chamber into combustion chamber 34 takes place with extremely high velocity turbulence and is rapidly mixed with the remaining air entering combustion chamber 34 through openings 36.

A variation in the construction of the precombustion chamber is illustrated in Figs. 3 and 5. Chamber 38 is shown having perforations

or holes 40 about its circumference which extend over the greater portion of its length. Cap 42 is provided over the downstream end of the precombustion chamber and this cap is provided with a series of holes 44 similar to those in member 38. Other variations in the arrangement and size of the perforations can be used with equal success.

While there has been illustrated and described a particular mechanical embodiment of the idea of the invention, it is to be understood that the invention is not limited to the particular mechanical embodiment so illustrated and described, but that such changes may be resorted to as come within the scope of the appended claims.

I claim:

1. A burner unit comprising an outer casing, an inner casing, the inner casing defining a combustion chamber, a precombustion chamber mounted within the inner casing and at the inlet to the combustion chamber, the precombustion chamber being cylindrical in form and having a plurality of holes over the greater portion of its length, the downstream end of said precombustion chamber being closed by a cap having a plurality of holes therein, means for supplying combustion supporting gases to the burner unit, means for diverting a portion of the combustion supporting gases into the precombustion chamber, the precombustion chamber being spaced from the inner casing inlet so that a portion of the combustion supporting gases entering the precombustion chamber can enter the area surrounding the precombustion chamber, an annular passage between the inner and outer casings for the flow of combustion gases therethrough, the inner casing having openings through which combustion supporting gases in the annular passage can be admitted to the combustion chamber.

2. A burner unit comprising an outer casing, an inner casing, the inner casing defining a combustion chamber, a precombustion chamber mounted within the inner casing and at the inlet to the combustion chamber, the precombustion chamber being cylindrical in form and having a plurality of holes over the greater portion of its length, the downstream end of said precombustion chamber being closed by a cap having a plurality of holes therein, means for supplying combustion supporting gases to the burner unit, a conical shield for diverting a portion of the combustion supporting gases into the precombustion chamber, the precombustion chamber being spaced from the inner casing inlet so that a portion of the combustion supporting gases entering the precombustion chamber can enter the area surrounding the precombustion chamber, an annular passage between the inner and outer casings for the flow of combustion gases therethrough, the inner casing having openings through which combustion supporting gases in the annular passage can be admitted to the combustion chamber.
